UNITED STATES PATENT OFFICE.

WILLIAM H. BENTLEY AND JOHN E. ROBERTS, OF JAMESTOWN, NEW YORK.

VEHICLE-HUB.

SPECIFICATION forming part of Letters Patent No. 608,099, dated July 26, 1898.

Application filed July 19, 1897. Serial No. 645,123. (No model.)

To all whom it may concern:

Be it known that we, WILLIAM H. BENTLEY and JOHN E. ROBERTS, citizens of the United States, residing at Jamestown, in the county 5 of Chautauqua and State of New York, have invented certain new and useful Improvements in Vehicle-Hubs; and we do declare the following to be a full, clear, and exact description of the invention, such as will enable 10 others skilled in the art to which it appertains to make and use the same, reference being had to the accompanying drawings, and to the letters of reference marked thereon, which form a part of this specification.

15 Our invention relates to hubs for vehicle-wheels, especially bicycle-wheels.

It consists in an improved device for attaching the spokes to the hub, as hereinafter set forth, and particularly pointed out in the 20 claims.

Heretofore bicycle-hubs have been made in the form of a shell or barrel with an external bead rolled near each end, in which eyes were made to receive the ends of the spokes. The 25 ball-cases were inserted into the ends of the hub and served to prevent dirt from entering the bearings through the spoke-holes. Other hubs have toothed collars formed integral with the shell of the hub, the spokes being 30 inserted through eyes in the teeth. Other hubs have studs projecting through holes in a plain shell, the studs having heads on the inside and being held in place by a sleeve or bushing under these heads. The spokes pass 35 through eyes in the projecting ends of the studs. Other hubs have flanges integral with the shell and perforated to receive the spokes. In all these constructions and others familiar 40 to us there are serious objections. With some dirt can work into the bearings. With others the tearing out of the spoke-eye ruins the entire hub. With others it is awkward work to insert a new spoke. Our invention aims to obviate all these difficulties.

45 Our hub is composed of a shell having at each end a spoke connection separate and detachable from the shell. It is capable of being made in several different styles to suit different makes of wheels and different modes 50 of attaching the spokes.

In the drawings, Figure 1 shows a side ele-

vation of a hub embodying our improvements. Fig. 2 is a longitudinal section thereof. Fig. 3 is a section of the spoke-connecting ring. Figs. 4, 5, and 6 show modified forms of rings. 55

The barrel of the hub is composed of a cylindrical shell A, which may be a piece of tubing turned to shape or it may be finished up from a solid bar of steel. It has near each end a collar a, the periphery of which is 60 slightly coned or tapered toward the adjacent end of the shell. At the outer edge of the collar is an abrupt shoulder a', beyond which the shell tapers perceptibly to its extremity. In the shell of a rear or driving wheel hub this 65 final tapered portion a² is omitted at one end, the shell being provided with two cylindrical shoulders, the outer one slightly smaller than the other. In the larger shoulder is cut a right-hand screw-thread to receive the threaded hub of a sprocket-wheel B. The smaller shoulder is given a left-hand screw-thread to receive a locking-nut C.

Our spoke connection is a ring D, which surrounds the collar a and fits tightly thereon 75 by what is known as a "force fit." The ring may be of the form shown in Figs. 1, 2, and 3, in which it is semicircular in cross-section, the diameter of the opening between the inner edges d being more than that between 80 the outer edges d', so that the edge d' forms a flange to fit the taper a², while the edge d fits the inner part of the collar a, as clearly shown in Fig. 2. The ring is turned a trifle smaller than the parts of the sleeve it is to 85 fit, and is then pressed on by a mechanical forcing device until the flange d' abuts closely against the shoulder a'. The inner edge d will then be in line with the edge of the collar a, so that the exterior of the combined 90 shell and ring will present a smooth and elegant appearance. The sprocket B screws tightly against the ring D at that end of the hub and assists in holding it in place. Moreover, the ball-cases E when pressed into the 95 ends of the shell expand the shell about half a thousandth of an inch, and this assists in securing the ring D. In addition the pull of the spokes when the wheel is laced up is in a direction tending to hold the ring against the 100 shoulder a'.

In the hollow bead-like ring (shown in Figs.

1, 2, and 3) we have provided keyhole-eyes d^2 for spokes having bent ends. If a plain flanged ring is preferred, the construction can be modified accordingly, as shown in Fig. 5. Here the ring is solid, with a wide slightly tapered hub to fit the collar a and a flange d^3 to abut against the shoulder a' . The outer portion of the ring is thinner and has transverse eyes d^4 for the spokes F. If straight tangent spokes are desired, the ring can be made as shown in Fig. 5, having regularly spaced teeth or lugs d^5 , with eyes for the spokes F. This style of ring can be made with a flange d^3 , as in Fig. 4.

15 Another style of ring is shown in Fig. 6, where the hollow head of Fig. 3 is provided at regular intervals with holes through which project studs G, having internal heads g and spoke-eyes g' in their outer portions. This 20 style can be used with straight spokes, the studs being staggered to permit the spokes to pass by each other, as shown by dotted lines in Fig. 6.

The chief advantage of our invention is 25 that if a spoke-eye tears out the damage can be repaired by simply putting on a new ring D. With many other styles of hubs it is necessary to replace the entire hub in case of such an accident. Another advantage is the 30 complete protection of the ball-bearings from dirt, since the shell is not perforated. Moreover, the ball-cases can be taken out without disturbing the spoke connections. In addition we find this hub convenient to build and 35 strong and durable in use. Its adaptability to the different modes of attaching spokes now in use is not the least among its valuable features.

It will be observed that the ring D is held 40 on the hub solely by the friction between it and the shell without any other fastening. This obviates all danger of the ring getting loose, as would be the case if rivets, screws, bolts, or nuts were used to secure it. It is, 45 however, solid and strong and yet readily removable by pressure in a hydraulic press or other mechanical forcing apparatus.

Having thus described our invention, what

we claim, and desire to secure by Letters Patent, is—

50 1. A vehicle-hub having a shoulder, and a hollow spoke-connecting ring detachably secured on said hub by a force fit only, the inner diameter of the outer edge of said ring being less than that of the other edge, thereby forming an inwardly-projecting flange 55 abutting against the shoulder on the hub, substantially as described.

2. A spoke-connecting ring having around one edge an inwardly-projecting flange whose 60 inner diameter is less than that of the other edge, in combination with a shell, having a shoulder against which said flange abuts, both edges of said ring having a force fit on the shell, substantially as described. 65

3. A vehicle-hub comprising a shell having a collar near each end, a reduced portion beyond the collar having a shoulder, and a spoke-connecting ring adapted to pass over said reduced portion to fit upon said collar, with a 70 flange on the ring abutting against the shoulder, substantially as described.

4. A bicycle-hub, comprising a shell having a collar and a reduced screw-threaded portion beyond said collar, a spoke-connecting ring fitting the collar and having a flange 75 abutting against the outer edge of said collar, and a sprocket-wheel screwed upon the shell and clamping said flange against the collar, substantially as described. 80

5. A vehicle-hub, comprising a shell threaded at one end, hollow rings secured on the periphery of the shell near either end, one of said rings being adjacent to said threaded portion, and a sprocket-wheel fitting the 85 threaded end of the shell and screwing against the ring which is adjacent to the threaded portion, substantially as described.

In testimony whereof we affix our signatures in presence of two witnesses.

WILLIAM H. BENTLEY.
JOHN E. ROBERTS.
